UNITED STATES PATENT OFFICE.

EDWARD MOORE, OF NUTLEY, NEW JERSEY, ASSIGNOR TO METRO ELECTRICAL CO. INC., OF NEWARK, NEW JERSEY.

DESIGN FOR A RECEIVING SET FOR WIRELESS MESSAGES.

Application filed October 8, 1923. Serial No. 7,424. Term of patent 7 years.

To all whom it may concern:

Be it known that I, EDWARD MOORE, a citizen of the United States, residing at Nutley, in the county of Essex, State of New Jersey, have invented a new, original, and ornamental Design for a Receiving Set for Wireless Messages, of which the following is a description, reference being had to the accompanying drawing, forming part hereof.

The figure shows a plan view of the wireless receiving set, showing my new design.

I claim:

The ornamental design for a receiving set for wireless messages as shown.

In testimony whereof, I affix my signature.

EDWARD MOORE
